UNITED STATES PATENT OFFICE.

SAMUEL S. STOLP, OF MANSFIELD, OHIO, ASSIGNOR TO THE OHIO BRASS COMPANY, OF MANSFIELD, OHIO, A CORPORATION OF NEW JERSEY.

TROLLEY-CONDUCTOR INSULATOR.

Application filed November 30, 1923. Serial No. 677,636.

To all whom it may concern:

Be it known that I, SAMUEL S. STOLP, a citizen of the United States of America, residing at Mansfield, in the county of Rich-
5 land and State of Ohio, have invented cer-
tain new and useful Improvements in Trol-
ley-Conductor Insulators, of which the fol-
lowing is a specification.

My invention relates to insulators and
10 more particularly to that class of insulators
used in connection with overhead electric
railway trolley lines wherein the trolley
wire is sectionalized and the sections fed
by a feeder system.
15 One object of my invention is to provide
a device to be inserted between the adjac-
ent ends of two trolley sections whereby the
adjacent ends of the trolley wire may be
mechanically connected, but electrically sep-
20 arated.

Another object of my invention is to pro-
vide a continuous electrical contact for the
current collector in passing from one sec-
tion to the adjacent section.

25 Another object of my invention is to eli-
minate the excessive sparking when the cur-
rent collector leaves a live section.

Another object of my invention is to pro-
vide the current collector with current
30 should the car inadvertently stop with its
collector between the adjacent ends of two
sections.

Another object of my invention is to pro-
vide a metallic run which can be engaged
35 by the current collector in passing from
one section to another in order to avoid de-
preciation which is found upon an insula-
tor in which the current collector passes
from one section to another in contact with
40 an insulating material.

A still further object of my invention is
to provide an insulator which can be used
with either a wheel or sliding collector with-
out any alterations or changes.

45 A still further object of my invention is
to produce a device in which the mechani-
cal strength is materially increased through
the relative arrangement of the parts as
hereinafter described.

50 Another object of my invention is to pro-
duce a device which is simple, efficient, easy
of installation and of low cost.

My invention resides in the new and novel
construction, combination and arrangement
55 of the various parts hereinafter more fully

described and disclosed in the accompanying
drawings.

My invention is illustrated in the accom-
panying drawings in which:

Fig. 1 is a side view in elevation of my 60
invention.

Fig. 2 is a lower plan view of my inven-
tion.

Fig. 3 is an end view of my invention.

Figs. 4 to 7 are sectional views taken on 65
correspondingly numbered lines on Fig. 1.

In the preferred embodiment of my in-
vention I employ a central member 1 of
insulating material, preferably wood, on ac-
count of its cheapness, strength, durability 70
and ease of shaping, although other mate-
rials, such as fiber, hard rubber, etc. may
be used.

To each end of the insulating member 1
is secured an end member 2 provided with
a channel to receive the end of a trolley
wire 3. I have shown the simplest form
of securing the wire to the member 2, which
consists in inserting the trolley wire with
a right angle bent into horizontal and ver-
75 tical recesses, and then bending its upwardly
projecting end back on to the end member,
after which the lips 4 may be formed about
the wire 3 to present a smooth running sur-
face for the current collector. There are, 80
of course, other well known means of se-
curing the trolley wire to the end mem-
bers known to those skilled in the art, and
which have been in common use, but as my
invention does not reside particularly in 85
the method of attachment of the wire to the
end member, I have shown only a simple
arrangement. The inner ends of the end
members are divided so as to form a pocket
90 having side walls 5. The pocket receives
the end of the insulating member 1 and
is secured thereto by means of the bolts 6.
The end member 2 is provided with a run-
way 7 adapted to receive either the groove
95 of a wheel type current collector or the
contact element of a sliding collector.

Positioned on each side of the device is
a guide member 8. The guide member has
preferably an L shaped cross section al-
though other shapes may be substituted. 105
Each guide member is sufficiently long to
bridge the gap between the end members and
to overlap the end members for a distance.
One end of each guide member is secured
to one of the end members. I have shown the 110

guide members 8 as being formed separate from the end members and secured thereto, but it is also possible to form the end member with its guide member integral. In 5 the form shown, one end of the guide member is formed with a lug 9 provided with an aperture to receive the lower bolt 6 or the lug may be sufficiently long to include both of the bolts 6. The guide member is 10 also provided with a lug 10 projecting at a point between the inner end of the opposite end member 2 and the vertical transverse center line X—X of the device. The lug 10 is formed with an aperture and the 15 member 1 has a corresponding aperture through which passes the fastening bolt 11 by means of which the lug 10 is securely attached to the member 1.

It will be noted that the guide members 20 are strong and rugged and secured to the member 1 by means of the bolts 11 and to the member 2 by the bolts 6 in such a manner that if excessive strain in a longitudinal direction is brought upon the members 2. 25 tending to separate them, that the portion of the member 1 between the bolts 11 will be placed in compression and, therefore, materially add to the strength of the device as a whole, and particularly to the strength 30 of the attachment of the end members to the member 1 by the inter-locking of the members 8 in their connection to the member 1. Each guiding member is provided with an inwardly and upwardly projecting surface 35 12 so spaced and related to each other as to receive the periphery of a wheel type current collector. The end portions of each guide member are so shaped and formed with respect to the runway 7 that when a 40 wheel is passing from the member 7 to the members 8 or vice versa, the passage will be made with perfect smoothness and no tendency to cause the wheel to be thrown out of engagement with either of these members 45 and thereby break the continuity of the circuit between the wheel and the members. The lower edge 13 of the guide members are adapted to receive a sliding current collector and the lower edge 13 is so shaped at its 50 ends that the sliding collector will also pass from the member 7 to the members 8 or vice versa so gradually as to avoid any bounding of the current collector, and hence avoid the forming of an arc.

55 There is an advantage in having the faces 12 sloping with respect to each other as it assures the wheel collector engaging with both of the members 8 throughout its travel from one member 2 to the other member 2 as the sloping face 12 on each member 8 tends to permit the collector to slide upwardly, hence into engagement with the face 12 of the other member 8.

60 As it is advisable at times to take the weight of the device off the trolley wire 1

attach to the upper central portion of the member 1 a supporting element 14 secured thereto by a through bolt 15 and which member 14 may have a threaded recess to receive the supporting stud of an overhead 70 hanger.

It will be evident that when a current collector passes from one section to another, that it will not be deprived of current during its travel across the device and, therefore, 75 if the collector should come to rest at a point between the inner ends of the members 2, the vehicle to which it is attached will be able to start up and proceed, which is not the case with the section insulators now in 80 general use. It is also evident that the vicious arcing which is produced with the present type of insulator will be practically eliminated. Theoretically, the arcing would be eliminated absolutely in my device if the 85 potential of the two end members is the same, but as the probabilities are that there will be some difference of potential there will be arcing in proportion, but I have found that this difference of potential is as a rule very 90 low and in actual trial the arcing which does form is hardly discernible.

With the present devices in use, when the current collector leaves one of the end members the difference of potential is the maximum between that of the trolley wire and the ground and this is usually four hundred to six hundred volts or more, and when the collector breaks the circuit at the inner end of the end member while current is flowing, 100 an arc is formed which is in proportion to the current drawn and the maximum difference of voltage between the trolley wire and the ground. This is so great that in a short 105 time the inner end of the end member and the insulation are soon destroyed.

There are, of course, many modifications which those skilled in the art will have suggested to them when they read my disclosure, but I do not wish to be limited other than 110 by my claims.

I claim:

1. A section insulator comprising in combination means for holding the adjacent ends of a trolley conductor in fixed and insulated relation, and a pair of parallel guide bars laterally spaced from each other and from the said means adapted to guide either a grooved wheel or sliding current collector across the break in the line conductor, each bar being electrically connected to a different trolley conductor and normally insulated from each other. 115 120

2. A section insulator comprising in combination means for holding the adjacent ends of a trolley conductor in a fixed, insulated and aligned relation apart, and a pair of bars parallel to the conductor and laterally spaced from each other and from the said means and so further positioned and ar- 125 130

ranged as to guide either a grooved wheel or sliding current collector over the break and supply current to the collector while engaging the bars.

5 3. A section insulator comprising in combination means for holding the adjacent ends of an interrupted trolley conductor in fixed and insulated relation and a pair of laterally spaced and insulated guide bars 70 insulated from each other, parallel to the conductor and each provided with an inwardly and upwardly extending surface to receive the flanges of a current collector and guide it across the break.

10 4. A section insulator comprising in combination, means for holding the adjacent ends of an interrupted trolley conductor in fixed and insulated relation, a pair of laterally spaced and parallel guide bars insulated from each other and from the holding means by air insulation and arranged to be connected by a current collector and each bar having a surface to be engaged by a current collector, the said surfaces on the 80 bars so related that each surface tends to automatically move the current collector into engagement with the said surface on the other bar while the collector is moving over the break.

15 5. A section insulator comprising in combination, an insulating member, an end member secured to each end of the insulating member, a conducting guide member extending from each end member towards 90 the opposite end member and spaced laterally from the insulating member, each guide member presenting an obliquely disposed face to be engaged by a current collector, the faces so related that each face operates 100 to move the collector into engagement with the face of the other guide member as the collector moves across the break.

20 6. A section insulator comprising in combination, an insulating member and an end member secured to each end of the insulating member to receive and hold in fixed and insulated relation the adjacent ends of an interrupted trolley conductor, insulated, parallel and longitudinally disposed guide bars secured to and spaced from the insulating member, each bar being of sufficient length to overlap the inner end of each end member and each bar electrically connected to a different end member.

25 7. A section insulator comprising in combination, an insulating member, an end member secured to each end of the insulating member to receive and hold in insulated relation the adjacent ends of an interrupted trolley conductor, a pair of parallel, laterally spaced guide bars overlapping the inner 110 ends of each end member and insulated from each other and to be engaged by a current collector and so related to the end members 115 that the current collector will simultaneous-

ly engage the inner surface of each bar and one end member, then engage the inner surface of the two bars and then engage the inner surface of the two bars and the other end member in passing across the 70 break from one end member to the other end member and to also electrically connect the conductors in making said passage.

8. A section insulator comprising in combination, a pair of end members to receive 75 the adjacent ends of a trolley wire, an insulating member securing the end members in a spaced and insulated relation, a conductor projecting and spaced laterally from each end member but on opposite sides of the insulating member, and extending longitudinally and parallel of the insulating member and overlapping the opposite end member to guide a wheel or a sliding collector from one end member to the other. 85

9. A section insulator comprising in combination, an insulating member, an end member secured to each end of the insulating member and having means to receive and secure a trolley wire thereto, means positioned on opposite sides of the insulating member and insulated from each other and having one end secured to an end member and having an attachment to the insulating member at a point beyond the transverse diametral plane to interlock the last said means with each other in insulated relation and having a contact surface which slopes inwardly and upwardly to engage a current collector in passing from one end member to the other. 95

10. A section insulator comprising in combination, an insulating member and an end member on each end of the insulating member to receive and maintain the adjacent ends of a conductor in an insulated and fixed relation, means projecting longitudinally from each end member towards the other end member and along opposite sides of the insulating member to be engaged by a current collector and holding means for securing the projecting means to the insulating member in spaced relation thereto and securing means passing transversely through the insulating member to 105 secure the holding means to the insulating member, the said securing means for each projecting means being positioned between the transverse diametral plane of the insulating member and the inner end of the 110 opposite end member to place that portion of the insulating member between the securing means under compression when the end members tend to move away from each other and to interlock the projecting means 115 with each other in insulated relation. 120

125 In testimony whereof I affix my signature.

SAMUEL S. STOLP.
